UNITED STATES PATENT OFFICE.

BENJAMIN F. MALOTT, OF GREENVILLE, SOUTH CAROLINA, ASSIGNOR OF ONE-FOURTH
TO JAMES A. NORRIS, OF PELZER, SOUTH CAROLINA.

RAIL-JOINT.

1,258,586.

Specification of Letters Patent.

Patented Mar. 5, 1918.

Application filed March 24, 1917. Serial No. 157,154.

To all whom it may concern:

Be it known that I, BENJAMIN F. MALOTT, a citizen of the United States, residing at Greenville, in the county of Greenville and 5 State of South Carolina, have invented new and useful Improvements in Rail-Joints, of which the following is a specification.

The present invention relates to improvements in rail joints.

10 In carrying out my invention it is my purpose to join the meeting ends of two railway rails in a thoroughly effective and practical manner so as to effectively hold the same against sinking or lateral movement, but at the same time providing for a limited longitudinal movement incident to the expansion and contraction of the rails.

15 It is also my purpose to produce a joint for two rails of the ordinary construction, 20 by so cutting the ends of the said rails as to provide an interlocking engagement therebetween and to further arrange upon the ends of the rails a chair member with which the rails co-act in such a manner as to insure the positive alinement of the said rails 25 against danger of either lateral or vertical displacement and without the employment of the usual fish plates and the connecting means therefor passing through the webs of 30 the rails.

It is a still further object of the invention to produce a rail joint wherein the meeting ends of the rails are such as to co-engage one with the other and to provide 35 a joint chair of a novel construction having a flange upon its outer face engaging with the rails whereby to insure the rails against tilting in an outward direction and also whereby to positively hold the 40 rails against movement in any direction except in a limited longitudinal direction.

With the above and other objects in view the improvement resides in the construction, combination and arrangement of parts set 45 forth in the following specification and falling within the scope of the appended claim.

In the drawings:

Figure 1 is a perspective view of the improvement,

50 Fig. 2 is a sectional view approximately on the line 2-2 of Fig. 1,

Fig. 3 is a perspective view of one of the rail ends,

55 Fig. 4 is a similar view of the co-acting rail end,

Fig. 5 is a perspective view of the joint chair, and

Fig. 6 is a perspective view of a modified form of the chair member.

The rail 1 has its head and web projecting a suitable distance beyond the base flange thereof, the said web being also cut to provide a depending lug 3 formed in a line with the end of the head and being further cut to provide a slot or opening 4 arranged inwardly of the lug 3 and the inner wall of the said opening 4 is in a line with the end of the base flange of the rail, while the lower edge of the lug 3 is arranged approximately central of the web of the rail. 70

The rail 2 has its web and base flange extending a suitable distance beyond its head, and the web in a line with the end of the head is cut away to provide a depression or opening 5 of a size to receive the lug 3 of the rail 1, while the outer corner of the web of said rail 2 is thus provided with a lug 6 which is adapted to be received in the opening 4 in the rail 1. It is, of course, to be understood that sufficient play is arranged 80 between the lugs and the openings in which they are received to permit of the limited longitudinal movement of the rails, incident to the contraction and expansion thereof, but the outer edges of the lugs rests one upon 85 the lower wall provided by the opening 5 and the other against the under face of the head of the rail 1, as clearly disclosed by the drawings.

The base flanges of the rails 1 and 2, to the opposite sides of the ends thereof are provided with spaced notches 7-7 which are adapted when the rails are assembled to align with similar notches 8 formed adjacent the opposite ends of the base plate 9 of the 90 chair member 10. The chair 10, upon its inner edge is formed with a right angular flange 11 and upon its outer edge with a vertically extending portion 13 terminating in an angular flange 14, and if desired, the said 100 angular flange may have its inner edge formed with a vertically extending plate 15 as illustrated in Fig. 6 of the drawings. The distance between the flanges 11 and 13 approximately equals the width of the base flanges of the rails 1 and 2 and the flange 11 is preferably constructed of spring material whereby the same will yield to permit of the rails being inserted into the chair, and which will also cause the frictional engagement be- 110

- 5 between the said flange 11 and the flange 13 when the rails are received upon the chair either when inserted into the chair or the chair moved longitudinally over first one of the rails and then brought likewise to engage with the other rail end. The angular flange 14 is provided with openings 16 alining with the openings 8 arranged in the base 9 of the chair and disposed below the said flange 14, 10 and spikes 17 are passed through the openings in the chair 10 and the notches in the edges of the base flanges of the rails, the said spikes entering the ties 2, as illustrated in the drawings.
- 15 From the above description, taken in connection with the drawings, the simplicity of the device, as well as the advantages thereof will, it is thought, be perfectly apparent to those skilled in the art to which such invention appertains without further detailed description.

Having thus described the invention, what I claim is:

20 A rail chair comprising a plate of uniform thickness throughout its area, said plate having a plane rectangular base portion and provided at one edge thereof with an upstanding flange which extends from end to end of the base portion and which lies in a 25 plane at a right angle to the plane of the base portion, said base portion having at its

opposite edge an upstanding vertical portion which extends from end to end of said base portion and which is parallel with said flange and of the same vertical length as the 35 flange, the said vertical portion merging at its upper portion into an inwardly disposed flange which is inclined with relation to the plane of the base portion, the inner part of the last mentioned flange merging into a 40 vertically disposed plate section which lies in a plane at a right angle to the plane of the base portion and at one side of the median line thereof, the ends of the second mentioned flange and the plate section being 45 spaced and disconnected from the base portion thereby providing room and space at one side of the chair whereby it may be forced laterally and spring in position under and about the meeting ends of adjacent rails 50 without separating or disturbing the alinement of the rails, the said base portion being provided in the vicinity of the first mentioned flange with spike openings and in the vicinity of the said vertical portion with 55 similar openings, and the second mentioned flange having spike openings which register vertically with the last mentioned spike openings in the base portion.

In testimony whereof I affix my signature. 09

BENJAMIN F. MALOTT.
